US00D693321S

(12) **United States Design Patent**
Zelazowski

(10) **Patent No.:** **US D693,321 S**
(45) **Date of Patent:** **** Nov. 12, 2013**

(54) **GROOVED MAGNET**

(71) Applicant: **Chemistrie Properties, Inc.**, Pittsburgh, PA (US)

(72) Inventor: **Dennis G. Zelazowski**, Pittsburgh, PA (US)

(73) Assignee: **Chemistrie Properties, Inc.**, Pittsburgh, PA (US)

(**) Term: **14 Years**

(21) Appl. No.: **29/453,859**

(22) Filed: **May 3, 2013**

Related U.S. Application Data

(60) Division of application No. 29/342,717, filed on Aug. 31, 2009, now Pat. No. Des. 684,942, which is a continuation of application No. 11/458,239, filed on Jul. 18, 2006, now Pat. No. 7,600,870.

(57) **CLAIM**

The ornamental design for a grooved magnet, as shown and described.

DESCRIPTION

FIG. 1 is a perspective view of the grooved magnet embodying my new design as claimed herein.

FIG. 2 is an angular side view of the grooved magnet shown in FIG. 1.

FIG. 3 is a top view of the grooved magnet shown in FIG. 1.

FIG. 4 is a bottom view of the grooved magnet shown in FIG. 1.

FIG. 5 is a planar side view of the grooved magnet shown in FIG. 1.

FIG. 6 is a perspective view of an alternate embodiment of the grooved magnet shown in FIG. 1.

FIG. 7 is an angular side view of the grooved magnet shown in FIG. 6.

FIG. 8 is a top view of the grooved magnet shown in FIG. 6.

FIG. 9 is a bottom view of the grooved magnet shown in FIG. 6; and,

FIG. 10 is a planar side view of the grooved magnet shown in FIG. 6.

1 Claim, 2 Drawing Sheets
